UNITED STATES PATENT OFFICE.

TILLMON PERRY RICKS, OF SAN MARCOS, TEXAS.

MEAT-CUTTER.

SPECIFICATION forming part of Letters Patent No. 463,255, dated November 17, 1891.

Application filed July 13, 1891. Serial No. 399,308. (No model.)

To all whom it may concern:

Be it known that I, TILLMON PERRY RICKS, a citizen of the United States, residing at San Marcos, in the county of Hays and State of Texas, have invented certain new and useful Improvements in Meat-Cutters; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention has relation to meat-cutters; and it consists in the novel construction and arrangement of its several parts hereinafter described.

In the accompanying drawings, Figure 1 is a top plan view of my invention with the lid thrown back. Fig. 2 is a longitudinal sectional view of Fig. 1, cut on the line *xx*. Fig. 3 is an enlargement of a part of Fig. 2. Fig. 4 is a detail view showing the knives *C*, cog-wheel *e*, bearing *c*, and cap *c'*. Fig. 5 is a cross-section of a part of the invention in order to show the groove in the track *b* and one of the wheels *b'*.

My invention is a meat-cutter for making beefsteak and other meats tender, which is done by running the meat back and forth under the knives and cutting the meat both ways if need be. In the invention shown there is but one cog-wheel and one cog-bar; but I put a cog-wheel on each end of the axle and a cog-bar on each side of the meat-board.

My invention is described as follows: The frame consists of two parallel side bars *a* *a* and end bars *a'* *a'* and has on each side a grooved rail *b* *b* and on each end rubber (or other suitable material) bumpers *b'* *b'*. These rails and bumpers are on the inside of the frame. The side rails *a* are provided with flanges *a*² to keep the meat-board in place. On either side of said frame is erected a bearing *c*, Fig. 5, for the end of the axle *d*, which carry the cog-wheel *e* and knives *f*. Said axle is held in place by the cap *c'*, which is secured by proper hinges and hasps. The cog-wheel *e* is rigidly secured on one end of the axle *d*, and I secure a similar cog-wheel on the other end of the axle. The knives *f* are circular and are also rigidly secured on the

said axle *d*. The cleaners *g* are bent downward at their center and pass under the said axle *d* and have a part cut away from each edge, 55 so that when the knives are put between them they exactly fit between the said cleaners, and thus the knives up to their very edges are closely embraced by the said cleaners, so that no meat can possibly pass up and follow 60 the knives around. The axle *d*, with its wheels and knives, can be easily taken out and cleaned by unclasping the caps *c'*. (See Fig. 5.) One end of the cleaners *g* is secured to a bar *h'*, that is as long as the machine is 65 wide, and has near each end a hook-catch *h*³, that enters a corresponding opening in the bar *h*². The other ends of said cleaners are secured to a bar *i'*, which bar is provided with a proper hasp *g*², which passes over a hook 70 or staple *j'* to keep that end of the cleaners down. Said beams *h'* and *i'* respectively rest on cross-bars *h*² and *i*², and said cross-bars *h*² and *i*² rest on arms *i*³, (see Fig. 2,) the lower ends of which are secured to the sides of the 75 standard *c*.

When I wish to remove the cleaners to clean them, I turn back the cover *k* and take out the axle *d*, with its attachments. Then I release the hasp *j*², turn back the cleaners, and withdraw the curved pins *h*'. Thus the cleaners are entirely separated from the machine.

Immediately under the knives is the moving meat-board *l*, having the side flanges *l*¹ to keep the meat from rubbing against the flanges *a*². Said board is also provided with a cog-bar *l*², the cogs of which mesh with the cogs on the wheel *e*. The opposite side of said board is provided with a cog-bar similar to bar *l*². On the under side of said meat-board are journaled four wheels *l*³, which run on the tracks *b* and carry said board. On the under side and near each end of said board are secured stops *l*⁴, which strike against the bumpers *b*. The axle is provided with the 90 crank-handle *m* or other proper means for revolving it.

My machine is operated as follows: The cleaners are put in place and the cover let down. The meat is then put on the board *l*. 100 The knives are then revolved back and forth, which operation carries the meat back and forth under them until it is lacerated sufficiently in one direction, and then turned and

lacerated crosswise, and, if need be, turned over and lacerated on the other side. When I wish to remove the meat-board I run it to one end of the frame, raise the end a little with one hand, and give the crank *m* a little turn, and it comes out. So my invention is arranged that every piece may be easily and readily taken out to be cleaned or repaired, and my cleaners are so constructed that they embrace not only the sides of the knives, but the edges, and thus not only keep them clean, but have a tendency to keep them sharpened.

Having described my invention, what I claim as new, and desire to secure by Letters

15 Patent, is—

The combination of the frame having the inner tracks *b b* and the bumpers *b' b'*, the meat-board *l*, having the side flanges *l'*, cog-bars *l²*, wheels *l³*, and stops *l⁴*, cleaners *g*,

adapted to closely embrace the knives *f* and 20 having one end secured to the beam *i'* and the other to the beam *h'*, curved hooks *h³*, secured to the lower face of said beam *h'* and adapted to enter perforations in the beam *h²*, axle *d*, working in the bearings *c*, cog-wheels 25 *e*, rigidly secured to said axle, circular knives *f*, adapted to fit in the openings between the cleaners *g*, cover *k*, hinged to the beam *h'*, and crank *m* on one end of the axle *d*, substantially as shown and described, and for the 30 purposes set forth.

In testimony whereof I affix my signature in presence of two witnesses.

TILLMON PERRY RICKS.
